HEATING APPARATUS

Patrick Joseph Young, New Rochelle, N. Y.

Application July 21, 1932, Serial No. 623,800

1 Claim. (Cl. 126—116)

This invention relates to heating apparatus, and more particularly to heating apparatus for heating dwelling houses by the forced draft circulation of warm air.

5 In general, the object of the invention is to provide a novel and superior heating apparatus for the purpose specified which may be economically manufactured, and operated with maximum efficiency and economy.

10 With this general object in view and such others as may hereinafter appear, the invention consists in the heating apparatus and in the various structures, arrangements and combinations of parts hereinafter described and particularly defined in the claim at the end of this specification.

15 In the drawings illustrating the preferred form of the invention, Figs. 1 and 2 are longitudinal sectional views through the heating apparatus, taken on planes at right angles to one another.

20 Various forms of heating apparatus have been heretofore used for heating dwelling houses, among which may be mentioned radiation systems comprising hot water, steam or vapor sys-

25 tems, all of which necessitate elaborate piping and the use of radiators in the rooms of the dwelling houses and do not lend themselves to conditioning of the air. In addition, hot air gravity furnaces have been utilized.

30 In these furnaces the air circulation is maintained by the buoyancy of the warm air, or in other words by gravity, and these systems have necessitated the employment of relatively large ducts, large heaters, an individual duct from the heater to each

35 register, and the use of relatively large registers in the floor or lower portion of the wall of the room. This type of heating apparatus leaves much to be desired for the reasons that the circulation of the air is sluggish, it is difficult to

40 get heat to extreme portions of the system, particularly to those portions of the houses exposed to the winter winds; these systems have been dusty, filtering of the air is not feasible, and the temperature of the air leaving the register is

45 relatively high. While this type of heating apparatus lends itself to economical production and relatively low-priced installation, its use has been restricted to the more inexpensive type of dwelling house.

50 More recently there has been developed a form of heating apparatus which is more commonly known as a forced draft heating and air conditioning system, operating upon the fundamental principle of forcing air under pressure through a heat exchanger to absorb heat sup-

plied by a source of fuel in the air being circulated therethrough. In practice the commercial forms of this type of apparatus have utilized gas as the fuel, although more recently there has been a growing tendency to put known forms of oil burners in existing air heating and conditioning apparatus of this type. However, the cost of the heating plant plus the cost of the separate oil burner installation results in the exceedingly high first cost for the combined apparatus. In addition the use of oil burners with existing types of air heating and conditioning apparatus has not proven entirely satisfactory irrespective of the cost, particularly in regard to the development of leaks by reason of the expansion and contraction of the cast-iron sections of the heating apparatus due to the intermittent operation of the oil burner together with the fact that the oil burner is usually noisy and the air circulating ducts accentuate the sound from the burner, and for the further reason that the efficiency of the unit is relatively low because of the fact that the burner and the heater are not designed for one another.

55 In accordance with the present invention, a forced draft heating apparatus particularly suitable for domestic air conditioning purposes is provided and in which a positive circulation of air under pressure is effected in contact with any usual or preferred form of heat exchange to the end that the air being circulated may be heated. Provision is made for utilizing a portion of the air thus heated and circulated, for supporting combustion of oil in an oil burner located within the heater for furnishing the heat to heat the general circulation of air. As a result I have found it possible to provide a heating apparatus which is suitable for use for general air conditioning purposes and in which the oil burner forms an integral part of the apparatus, and the air for supporting the combustion of the oil in a pre-heated and most desirable condition may be conducted to the burner without the necessity of the employment of the usual form of blower and attachments forming part of the oil burners now on the market.

Referring now to the drawings, which as above stated illustrate the preferred embodiment of the invention, the present apparatus is provided with a combustion chamber indicated generally at 10 within which an oil burner indicated generally at 12 is operatively supported. The apparatus is also provided with means for forcing air under pressure therethrough in a manner such as to permit the air to be heated by the heat generated 50 55

by the operation of the oil burner. As illustrated in Figs. 1 and 2, the apparatus is provided with a fan or blower of any usual or preferred construction indicated at 14, and the discharge side 5 15 of which is connected to the air conduit 16 of a heat exchanger 18. The air conduits 16 are preferably composed of metal arranged to permit the passage between contiguous portions 10 of the air conduit of the gaseous products of combustion which rise through a tortuous flue 19 around and between such portions of the air conduit until finally the products of combustion pass out through the flue 20 connected to the chimney. 15 As a result of this construction, the air passed 15 through the air conduit from the fan or blower 14 is heated by conduction by the products of combustion of the oil, the exchange of heat taking place on the counter-flow principle. In other words, the air entering the apparatus from the 20 blower or fan first comes in contact with the heating surfaces of the heat exchanger which in turn are heated by those products of combustion about to leave the apparatus, and as the air continues to pass through the heat exchanger its temperature 25 is gradually raised, coming in contact with heating surfaces at progressive increasing temperatures until in the lower portion of the heat exchanger the air will have been brought to its higher temperature and will encounter heating 30 surfaces at the highest temperature which are heated by products of combustion at their highest temperature.

After the air has thus been heated by passing 35 through the heat exchanger, it is conducted from the apparatus herein shown as being passed through the pipe 40 to the heater discharge 42 connected to the duct system leading to the various rooms within the house.

From the description thus far it will be observed 40 that air enters the heat exchanger from the fan or blower at room temperature, as for example 65° F. and may be raised in temperature during its passage through the heat exchanger to a higher temperature, as for example 190° F. 45 In accordance with the present invention a portion of this air is utilized for the operation of the oil burner, and as herein shown, the air chamber of the burner is connected by a pipe 61 to the air conduit 40 leading from the heat exchanger and 50 through which the air is passing during the operation of the apparatus at a temperature of approximately 190°. As illustrated in Figs. 1 and 2, in the illustrated form of apparatus, the required quantity of this air of relatively high temperature 55 may be led off from the lower run of the duct 40 through the pipe 61 and conducted therethrough to the air chamber of the burner. The pipe line 61 may be provided with a control damper 63.

From the description thus far it will be apparent 60 that the present invention permits the construction of an oil burner and a heater as an integral unit instead of two separate units; that it reduces the first cost and permits the elimination of a duplication of parts; that it reduces the cost of installation because the installation consists of one operation instead of two separate operations, which in practice were usually done at different times; that it permits more efficient 65 operation because the air or combustion may be supplied at an elevated temperature preferably around 190° F. instead of at a temperature ranging from 40° to 50° as would otherwise be the case.

In the oil burners now on the market which withdraw cold air from the basement, a limit exists as to the amount of air which can be introduced without detracting from the efficiency of the combustion. When this limit is exceeded, the excessive cold air reduces the temperature in the burner retort, detracting from the vaporization of the oil, and preventing the burner from operating at maximum efficiency with the result that it has been impossible to approach complete combustion. By using pre-heated air at the temperature which may be obtained by the present apparatus, it is possible to introduce into the burner much higher volumes of air without cooling the burner retort, with the result that combustion more nearly approaching complete combustion may be obtained. 15

Provision is also made for controlling the supply of humidity to the air stream, and as herein shown a water line 100 is tapped into the air 20 conduit 16, and is provided with a solenoid valve 102 controlled by a humidistat.

From the description thus far it will be observed that the present invention enables heating apparatus to be provided which is capable of operating with increased efficiency because of the higher temperatures at which the air may be supplied for the operation of the burner, with the result that a greater supply of air can be provided to insure complete combustion without hazard of cold air cooling the flame and retarding the combustion. In addition, the present apparatus may be installed at a minimum first cost, resulting from the incorporation of the burner and heater into an integral unit and eliminating duplicate parts which are involved in the installation of a separate oil burner unit in a separate heater. Finally, the cost of installation is reduced and the whole heater may be operated within such limits of cost which greatly enlarges the commercial field of usefulness of the heater. 35

While the preferred embodiment of the invention has been herein illustrated and described, it will be understood that the invention may be embodied in other forms within the scope of the following claim. 40

Having thus described the invention, what is claimed is:—

In a unitary air heating apparatus for domestic air conditioning purposes, in combination, a casing providing a combustion chamber, a heat exchanging conduit entirely enclosed by the casing and provided with an inlet, and an outlet extending through the casing, said outlet being adapted to be connected to a duct system extending throughout the house, a blower connected to the inlet having capacity sufficient to circulate the air under pressure through the heat exchanging conduit and outwardly from said outlet through said duct system to effect the conditioning of the air within the house, an oil burner within the casing and underlying said heat exchanging conduit, and means for withdrawing sufficient heated air from the heat exchanging conduit at a point where it has been heated to a substantially maximum temperature to supply the entire amount of air for the combustion of oil in the oil burner, whereby the single blower effects both the circulation of the air throughout the house and the supply of the entire air required for the combustion of the oil by the oil burner. 55 60 65 70
